UNITED STATES PATENT OFFICE.

CHARLES STEPHENS, OF BARTON HEIGHTS, VIRGINIA, ASSIGNOR, BY MESNE ASSIGNMENTS, TO A. H. CALLIGAN, OF RICHMOND, VIRGINIA.

SIGNALING SYSTEM.

1,105,860.

Specification of Letters Patent. Patented Aug. 4, 1914.

Application filed August 31, 1909. Serial No. 515,431.

To all whom it may concern:

Be it known that I, CHARLES STEPHENS, a citizen of the United States, residing at Barton Heights, in the county of Henrico and State of Virginia, have invented new and useful Improvements in Signaling Systems, of which the following is a specification.

The invention relates to an improvement in signaling systems primarily adapted for the automatic control of block signals under the influence of moving trains.

The main object of the present invention is the provision of a signaling system particularly designed for use on single track railways in which home and distant or danger and caution signals are arranged, the system providing for the automatic operation of intervening distant or caution signals to set the same at caution position two blocks or signals in advance of the operating train, the system also providing for setting both the home and distant signals to danger positions when two trains are on the same track with a clear block between them. By this arrangement of the circuits and signals an operating train will set the second caution signal in advance of said train to caution position, while the presence of two trains in the terminal blocks of any three blocks will set both intervening danger signals to danger position, so that except through a disregard of signals it is impossible for two trains to approach closer to each other than the terminals of a single block.

The invention will be described in the following specification, reference being had particularly to the accompanying drawings, in which:

Figures 1 and 1^a represent a diagrammatic view, illustrating the various circuits of the system. Fig. 2 is an enlarged diagrammatic view, showing the track circuits. Fig. 3 is an enlarged diagrammatic view, representing the signal circuits.

The present invention is particularly directed to a system of electrical control for signal machines and in this connection it is to be understood that any commercial type of signaling machine may be used and that no particular machine is contemplated.

In carrying out the details of the present invention it will be understood that the circuits of each block are identical with the

circuits of every other block and hence a detailed description of one will suffice for all. In the instance shown the track is divided into a series of blocks 1, 2, 3, and 4, the rails of which are in insulated block sections and between each of which blocks are arranged signal stations A, B, C, and D, each including danger and caution signals 5 and 6 respectively. A common return service wire 7 is used for all blocks and in the following description will be hereinafter referred to as the common wire.

The circuits peculiar to each block include a track energizing circuit in which a battery 8 or other source of energy is connected by conductors 9 and 10 to the respective rails, this track circuit including an electro-magnet 11 connected by conductors 12 and 13 to the rails so that the electro-magnet is normally energized so long as there is no short circuiting of the source of energy by bridging the rails. A controlling relay 14 is arranged in each block circuit, said relay having a conductor 15 leading to the common wire and a second conductor 16 which leads to a block in advance, as will presently appear. Each block also includes a primary signal relay 17 having a conductor 18 connected to the common wire and a second conductor 19 which leads to a block in rear of the particular block, as will presently appear. A secondary signal relay 20 is also arranged in each block, having a conductor 21 leading to the common wire and a conductor 22 leading to a block in advance. It is, of course, to be understood that the various relays are arranged in a suitable group at the ends of the respective blocks, and as shown in the drawings each group will contain a portion of the relays of the two adjacent blocks, that is each group will contain the track relay and primary signal relay of one block and the controlling relay and secondary signal relay of the adjacent block in advance. In each group is arranged a circuit controlling the danger signal 5, which circuit includes a conductor 23 leading from the danger signal mechanism to an armature 24 arranged to be influenced by the controlling magnet 14 in said group, a contact point 25 engaged by the armature 24 when the controlling magnet is energized, a conductor 26 leading from the contact point, a conductor 27

leading to and through a source of energy, as a battery 28, a conductor 29 leading to and through an armature 30 controlled by the track magnet 11, a contact point to be engaged by said armature when the track magnet is energized and a conductor 31 leading to the danger signal operating mechanism. The danger signal circuit as thus outlined includes two breaks, one controlled by the track relay 11 and the other by the controlling relay 14. For the purposes of the proper control of the danger signal, as will presently appear, the main danger signal circuit just described must be provided with an auxiliary or secondary path, in order to require more than the operation of the controlling and track relays to set said signal. For this purpose a conductor 32 is connected to the conductor 23 adjacent the danger signal apparatus, leading to an armature 33 controlled by the primary signal relay 17, the auxiliary danger signal circuit also including a conductor 36 having a contact point to be engaged by the armature 33 and leading to and connected with the conductor 27 of the main danger signal circuit. It will be apparent from the above arrangement of danger signal circuits that the energy of the battery 28 may be directed to the danger signal controlling mechanism by either one of two paths, and that, therefore, the automatic breaking of the circuit of either path will not permit the signal to go to the danger position.

The caution signal of each casing is also independently controlled, said controlling circuit including a conductor 37 leading from the caution signal controlling apparatus to and through an armature 38 controlled by the secondary signal relay of the particular casing, to and through a conductor 39 leading to an armature 40 controlled by the primary relay signal 17 of the casing, to and through a conductor 41 terminating in a point to be engaged by the armature 40 when the primary signal relay is energized, and connected at the opposite end to the conductor 27 leading to the battery 28, it being understood that the return to the caution signal operating mechanism is by means of a conductor 42, leading from the conductor 31 previously described. The conductor 31 is extended beyond the signal operating mechanisms in the form of a conductor 43, which leads to and terminates in a point 44 designed to be engaged by an armature 45 controlled by the secondary signal relay, the armature being in circuit with a conductor 46 leading to and through an armature 47 operated by the controlling relay and to and through a conductor 48 connected to the conductor 29 between the battery 28 and the armature 30.

From the above description it will be evident that in order to set the caution signal

either the primary or secondary signal relay will have to be deenergized, the deenergization of either one preventing a flow of current to maintain the caution signal set at clear. To set the danger signal mechanism in danger position both the controlling signal relay and the primary signal relay must be deenergized, as upon the deenergization of either one the current can flow through the armature controlled by the other and maintain the signal set at clear.

As the signal circuits are thus each provided with main and auxiliary operating circuits separately controlled by different relays it is only necessary to provide for the deenergization of these relays in a particular manner in order to effect such operation of the respective signal circuits as may be desired. This object is gained by arranging one conductor of each of the relays of a group so that it may be controlled in a remote block, and this provision of circuits I shall now describe.

Assuming as a basis for the description, a particular signal set that for example including signals C, it will be seen that the conductor 16 leading from the controlling relay 14 is extended to the block in advance by a continuous conductor 59 which leads to and through a conductor 60 terminating in an armature 49 controlled by the track relay 11 of the block 3, the armature 49 being designed to engage a point forming the terminal of a conductor 50, which includes a battery 51, as a source of energy, and leads thence by a conductor 52 to the common wire. Beyond the juncture of the conductors 59 and 60 and connected at said juncture is a conductor 53, which leads to the primary signal relays 17 of the next advanced block 2, that is the conductor 53 from one block to the other is simply a continuation of the conductor 19 leading from the primary signal relay, as previously described.

The conductor 22 leading from the secondary signal relay of signal C is, by a continued conductor 54, carried to and through an armature 55 governed by the controlling relay 14 at station B, thence by a conductor 56 through a source of energy, as a battery 57, to and through a conductor 58 to the common wire.

Assuming a train in block 2, the operation incident to the travel of such train is as follows: The battery 8 of the block is short circuited and the relay 11 thereof deenergized. The armatures 30 and 49 are released. As the armature 30 controls simply one path of the circuit leading to the signals A these signals are not affected by such break. The break at the armature 49, however, disrupts the conductor 59 leading to the controlling relay 14 at station B. The deenergization of this controlling re-

lay drops the armatures 47, 24 and 55. The armatures 47 and 24 control single paths only of the signal circuits and hence the signals of block 3 are not affected. The release of armature 55, however, breaks the continuity of conductor 54, which controls the secondary signal relay 20 at station C. The deenergization of the secondary relay 20 of block 4 releases the armatures 38 and 45. The dropping of the armature 38, opens the caution signal circuit, and the caution signal at station C is set in caution position. Therefore, the presence of a train in block 2 sets the caution signal at station C. The dropping of armature 45 breaks at 44, the current path leading from the battery 28 through conductor 48, armature 47, armature 45 and conductor 43 to conductors 42 and 31; but as this break is in only one of the two paths leading from battery 28 to conductor 31, the danger signal is left in normal safety position. The conductor 42 is, for convenience, connected to the wires 31 and 43 leading to one side of the battery, and the breaking of one of these paths has no additional effect on the caution signal circuit, which has already been broken by the dropping of armature 38. If, however, while the first or controlling train is in block 2 a second train should enter block 4, said latter train would affect the circuits in the following manner. The deenergization of the track relay at station C would release the armatures 30 and 49. The presence of a train in block 4 by dropping the armature 30 cuts the only remaining path to the danger signal C, hence said danger signal is set in danger position. The deenergization of the track relay 11 at station C by dropping the armature 49 also deenergizes the primary signal relay 17 at station B. Deenergization of the primary signal relay at station B drops the armatures 33 and 40, and as the train in block 2 is holding the controlling relay 14 at station B broken, the armatures 24 and 47 of the signal circuits are, of course, dropped. The signal circuits are, therefore, broken at the armatures 24 and 47 by the train in block 2 and the armatures 33 and 40 by the train in block 4. The circuits of signal B are thus completely broken and the danger signal at station B goes to danger. Therefore, the presence of a train in block 2 and the presence of a second train in block 4 will set the two intervening signals at danger.

I claim:—

1. In a block signal system, a trackway divided into a series of blocks, signal mechanisms at the meeting ends of the blocks, each said mechanism including a translating device and a normally closed circuit holding said translating device normally energized and its signal at clear, and means controlled

by the presence of trains in any two blocks separated by one intervening block to break the circuits corresponding to the signals at the ends of the intervening block.

2. In a block signal system, a trackway 70 divided into a series of blocks, a signal at the meeting ends of each two blocks, closed signal-operating circuits each maintaining its signal at clear, each circuit being jointly controlled by the presence or the absence of 75 trains in one of two adjoining blocks and in a thereto non-adjoining block on the opposite side of the meeting end, and also jointly controlled by the presence or the absence of trains in the other of said adjoining blocks and in a thereto non-adjoining block on the opposite side of said meeting end.

3. In a block signal system, a trackway 85 divided into a series of blocks, a signal at the meeting ends of each two blocks, closed signal-operating circuits each maintaining its signal at clear, each circuit being jointly controlled by the presence or the absence of 90 trains in one of two adjoining blocks and in a thereto non-adjoining block on the opposite side of the meeting end, and also jointly controlled by the presence or the absence of trains in the other of said adjoining blocks and in a thereto non-adjoining 95 block on the opposite side of said meeting end, said circuit being further jointly controlled by the presence or absence of trains in both of said adjoining blocks.

4. In a block signal system, a trackway 100 divided into a series of blocks, a signal located at the meeting ends of each two blocks, a normally closed signal operating circuit maintaining each signal at clear, said circuit comprising a battery, and a motor, each 105 side of the battery connected to the motor by two current paths in parallel, a contact in each of the four current paths, an electromagnet for controlling each contact, the electromagnets for any given signal being 110 controlled by the presence or absence of trains in the blocks as follows, viz. the two magnets on one side of the circuit controlled respectively from one of the blocks at the right of the signal and a thereto non-adjacent block adjoining the block on the left of the signal, and the two magnets on the other side of the motor circuit controlled respectively from the block at the left side of the signal, and a thereto non-adjacent block adjoining the block at the right of the signal, whereby danger signals are set at the ends 115 of each block intervening between two occupied blocks adjacent said intervening block, irrespective of the direction of travel. 120

5. In a block signal system, a trackway divided into a series of blocks, home and distant signals and operating mechanism therefor at the meeting ends of each two adjoining blocks, closed signal operating circuits 125 130

maintaining each of said signals at clear, the home signal operating circuit being jointly controlled by the presence or the absence of trains in one of the two adjoining blocks and in a thereto non-adjacent block adjoining the block at the opposite side of the meeting end, and also jointly controlled by the presence or the absence of trains in the other of said adjoining blocks and in a thereto non-adjacent block adjoining the first mentioned block, the distant signal operating circuit being controlled by the presence or the absence of trains in either of the blocks next the two adjoining blocks.

6. In a block signal system, a trackway divided into a series of blocks, a series of signal stations, one at the meeting ends of each two blocks, each station having thereat a signal, operating mechanism therefor, a closed signal operating circuit including a battery, each side of the battery being connected to the signal operating mechanism by two parallel branches, and means for controlling the circuits comprising four relays at each station, viz. (1) a track relay at a block-end adjacent the station and controlling one of the parallel branches of the signal operating circuit and also the "controlling" relay at the station to the right, (2) a "primary" relay controlling another of the parallel branches of the signal operating circuit and controlled from the track relay at the station to the right, (3) a "controlling" relay controlled from the track relay at the station to the left and itself controlling a third one of the parallel branches of the signal operating circuit and the operating circuit of the "secondary" relay at the station to the right, and (4) a "secondary" relay controlled from the "controlling" relay at the station to the

left and controlling the fourth parallel branch of the signal operating circuit.

7. In a track signal system, a trackway divided into a series of blocks, a series of signal stations, one at the meeting ends of each two blocks, each station having thereat home and distant signals, operating mechanism therefor, closed signal operating circuits including a battery for maintaining said signals at clear, the home signal operating circuit comprising two parallel branches connecting each side of the battery to the home signal operating mechanism and means for controlling the circuits comprising four relays at each station, viz. (1) a track relay at a block-end adjacent the station and controlling one of the parallel branches of the home signal operating circuit and also the "controlling" relay at the station to the right, (2) a "primary" relay controlling another of the parallel branches of the home signal operating circuit and also the distant signal operating circuit and itself controlled from the track relay at the station to the right, (3) a "controlling" relay, controlled from the track relay at the station to the left and itself controlling a third one of the parallel branches of the home signal operating circuit and the "secondary" relay at the station to the right, and (4) a "secondary" relay, controlled from the "controlling" relay at the station to the left and controlling the fourth parallel branch of the home signal circuit and also the distant signal circuit.

In testimony whereof, I affix my signature in presence of two witnesses.

CHARLES STEPHENS.
